UNITED STATES PATENT OFFICE.

HEINRICH DREWELL, OF CHARLOTTENBURG, GERMANY, ASSIGNOR TO SCHNELLSETZ-MASCHINEN-GESELLSCHAFT MIT BESCHRANKTER HAFTUNG, OF CHARLOTTENBURG, GERMANY.

LINE-CASTING MACHINE.

1,097,707.

Specification of Letters Patent.

Patented May 26, 1914.

Application filed April 22, 1912. Serial No. 692,409.

To all whom it may concern:

Be it known that I, HEINRICH DREWELL, a subject of the German Emperor, residing at Charlottenburg, Germany, have invented 5 new and useful Improvements in Line-Casting Machines, of which the following is a specification.

This invention relates to line-casting machines in which the molds for making the 10 line-bodies are accommodated in a wheel or similar rotatable holder.

In my co-pending application Serial No. 574,256 of July 28th 1910 I have described a device for changing the mold in matrix-setting and line-casting machines, which allows to prepare a change of the mold at any moment during the setting of a line without interfering with the operation of the casting apparatus. With this device it 15 is therefore possible to change the body of the type and the mold simultaneously. In practical use it often happens, however, that the body of type has to be changed more frequently than the mold within quite a few 20 lines. When for example matrices carrying two intaglio-characters of different bodies are used the mold for the greater body must be also used for such lines which only contain few letters of the larger size, the 25 small type mold being only permissible for casting lines containing characters of the smaller body alone. To save the composer all consideration on this point and to get the utmost work out of the line-casting ma- 30 chine, as well as in order to adapt the latter for being automatically operated by means of perforated bands, my present invention provides an improvement of the apparatus described in the before-mentioned application, which automatically sets the mold in 35 conformity with the type used in each line.

In the construction shown in the drawings it is supposed that printing matter, containing characters of various body is 40 produced by matrices carrying two kinds of characters of varying heights, which, when setting lines of matrices, are assembled in different positions in such manner

that the character to be cast from a certain matrix always is correctly adjusted into the 50 casting line.

In the accompanying drawings Figure 1 shows a front view of the assembling elevator and the device for changing the position of the matrices; Fig. 2 shows a side 55 view of the device shown in Fig. 1 and the mechanism for operating the same; Fig. 3 shows the latter mechanism seen from the rear-side of the line-casting machine; Figs. 4, 5, and 6 show details.

The assembling elevator 1 for assembling the lines of matrices is provided with a lower guide 6, and a longitudinally movable rail 7, forming an upper guide for setting the matrices in two varying positions. If 60 the matrices are to be caught in the upper position the rail 7 is pushed forward in known manner toward the collecting-star 5. In its normal position, in which the matrices are collected on the lower guide 6, 65 there is a sufficient space between the hook 8 and the collecting star-wheel 5 to allow the matrices to fall on to the lower guide 6.

The rail 7 is operated by two angle-levers 10, 11 and 12, 13. The lever 10, 11 is pivotally mounted on a neck-screw 16 inserted into the body of the assembling elevator 1, and rests with its horizontal arm 11 on the arm 12 of the second angle-lever, the arms 12 and 13 of which are attached to and rotate with the shaft 14. To the arm 13 is attached the draw-rod 17, which connects the angle-lever 12, 13 with the lever 18, the latter being actuated by the cam-disk 19. Around the shaft 14 is arranged the torsion-spring 15 which tends to constantly hold the levers 10, 11, 12, 13 and 18 in such position that the rail 7 is held a distance 70 from the collecting star wheel 5, thus allowing the matrices to drop into the lower position. The cam-disk 19 and the disk 21 are both mounted on one shaft or spindle 20. On the disk 21 is pivoted a forked lever 22 (Fig. 5) which in turn bears a coupling catch 23. The catch 23 is situated opposite 75 to a crown-wheel 25 which rotates loosely

60

75

95

around the shaft 20 and is connected with the pulley 26, by which it is constantly driven. The catch 23 has a lug 27 and is actuated by the spring 28, by means of an intermediate pin 29 passing through a suitable hole in the cam-disk 21. On both sides of the cam-disks 19 and 21 are two levers 30 and 31 (Fig. 2) actuated by a common spring 32 and pivotally mounted on two neck-screws 33 and 34 on the main frame of the machine. The spring 32 tends to move the lower ends 35 and 36 of the levers 30 and 31 outward. The levers 30 and 31 have beveled faces 38 and 39 situated in the way of the rotating lug 27 of the coupling catch 23 and so arranged that the coupling catch 23, on turning around the shaft 20, engages with one of the said beveled faces and is thus withdrawn from the teeth of the crown-wheel 25. Below the ends of the levers 35 and 36 are the armatures 40 and 41 of the electromagnets 42 and 43. Each armature bears a pawl 44 and 45 respectively which, as long as the armature is not attracted, hold the two ends of the levers in position against the action of the spring 32. To each of the levers 30 and 31 are further connected the short arms 30^a and 31^a respectively, which are actuated by the projections 21^a and 21^b of the cam-disk 21 (Figs. 2 and 5), thus bringing the levers 30 and 31 back to their locked position after having been disengaged from the pawls 44 and 45 respectively.

35 The cam-disk 19 has a recess 19^a and a projection 19^b (Fig. 4). On its periphery the roll 60^a rests at the end of a rod 60, which is pivotally attached to the lever 18 and engages with its slotted end a pin 58^a at the lower end of the lever 58.

36 The electromagnets 42 and 43 may be controlled by perforations in a perforated band, which operates the machine, or by the hand of an operator by means of a suitable switching device. As these electromagnets form not properly a part of my invention they may be omitted and any suitable mechanism for operating the pawls 44 and 45 may be employed. When one of the electromagnets 42 and 43 is energized the respective lever 30 or 31 is released, and the cam-disk begins to move. If, for instance, the magnet 43 is energized the lug 45 will be disengaged from the lever-end 36. The lever 31 consequently rocks outward and retracts the beveled face 39 from the lug 27 of the coupling catch 23. Owing to the action of the spring 28 the latter engages in the crown-wheel 25 and is rotated with the latter. As a result of the rotation of the cam-disks 19 and 21 which now takes place, the latter first brings the lever 31 back into the locked position by means of the projection 21^a and the lever 31^a. During the further rotation 60 of the cam-disks the roll 60^a, which hereto-

fore has rested on the part 19^a of the cam-disk 19, runs on to the part 19^b, and at the same time the lug 27 engages with beveled face 38 on the lever 30, thus lifting the catch 23 out of the crown-wheel 25 and stopping the cam-disks 19 and 21. The rod 60 (Fig. 2) is pushed toward the right by this operation and actuates on the one hand the lever 18 and on the other hand the two-armed lever 58, by a neck-screw 58^a engaging the slotted end of the rod 60. The actuation of the lever 18 is transmitted to the angle-lever 12, 13 by the draw-rod 17 and by means of the further angle lever 10, 11 to the rail 7 the position of which is then changed. This causes the matrices in the assembling elevator 1 to be placed in their upper position on the rail 7.

37 A finger 57 of a lever 55 engages in the upper end of the two-armed lever 58. The lever 55 is pivoted on the lever arm 53 of the two-armed lever 52, 53 by a neck-screw 54 and moves on a right angle to the movement of the latter. A spring 77 which is attached to the lower arm of the lever 58 tends to hold the levers 58 and 55 in the position corresponding the normal position of the rail 7 in which the matrices are assembled on the lower guide 6 of the assembling elevator 1.

38 The double lever 49, 50 (Figs. 2 and 3) which for the purpose of changing the mold is caused to engage with the lug 85 on the line-transferring shaft 84, as described in detail in my before mentioned specification, 100 is pivotally mounted on the pin 51. The latter is situated in the forked end 52 of the two-armed lever 52, 53.

39 On the lever 55 is provided a lug 56 opposite to which are situated two toothed wheels 65 and 66 which are firmly connected one to another by an intermediate disk 67, in such manner that the teeth of one wheel are placed beside the gaps of the other. Both these toothed wheels are rotarily mounted on a common pivot 68. A spring-pressed pin 69 engages in suitable holes of the wheel 66, and serves to secure the position of the two wheels 65 and 66 against unintentional rotation. The lever 55 can be moved by the lever 58 and the rod 60 so that the lug 56 faces either the wheel 66 or the wheel 65. A pawl 71 which is pivotally attached to the lever-arm 49, engages in the gap between the teeth of the wheels 65 and 66. Each to-and-fro movement of the lever 49, 50 causes the pawl 71 to move forward about the width of one tooth of the wheels 65, 66 and to turn these wheels so that the lug 56 alternately faces a tooth and a gap, if the position of the lever 55 is not changed.

40 The lever-arm 53 is provided with an extension 53^a upon which engages a hook 72^a at the end of a rod 72, normally holding the 139

lever 53 in the lower position. Every time the assembling elevator 1 is raised to pass a line into the casting apparatus the rod 72 is raised by means of a lever 75 pivotally mounted on a pin 75^a, and connected with the assembling elevator 1 by the link 76, thus releasing the lever-arm 53. As a result of the greater weight of the lever 49, 50 mounted on the other lever arm 52, the lever-arm 53 turns on the pin 52^a. This movement can only take place, however, when the lug 56 is allowed to enter one of the gaps in the toothed wheels 65 or 66. If the lug 56 abuts against a tooth of one of the two wheels the movement of the lever 53, 52 is prevented. In the downward movement of the lever 49, 50 its lower end engages, in the manner described in the before-mentioned application, with a lug 85 on the line-transferring shaft 84 and thus causes the further necessary operations for the change of mold. Before starting, the wheels 65, 66 must be so adjusted by hand that the lug 56 faces a tooth of the wheel 65 or a gap of the wheel 66, when the mold for casting types of the higher body is in the normal position for use. When on the other hand the mold for casting the smaller letters is in that position, the lug 56 should face a tooth of the wheel 66 or a gap of the wheel 65.

The position of the lever 55 depends on the type employed, and that of the wheels 65 and 66 on the mold used. If the mold in working position does not correspond to the height of type used within a line, a change of mold takes place, the lug 56 entering a gap in the double wheel 65, 66, and causing the downward movement of the lever 49, 50, and the further processes described in the before-mentioned application.

It must be considered that the mold for casting the thicker line-body should also be employed in such cases when only a few characters of the higher body occur in a line; therefore when the end of the line contains characters of the smaller body only, after completing such line the position of the lever 55 must nevertheless be that required for characters of higher body. For this purpose a locking device is provided which holds the lever 55 in the position required for the higher characters until the end of the line, when it has once been set in this position while composing the line. This locking device consists of the catch 78 which forms one arm of the angle-lever 78, 79 and is capable of engaging a lug 80 on the lever 58 as soon as the latter lever arrives in the position corresponding to the higher characters. The catch 78 then prevents the return of the lever 55 into the position corresponding to the smaller characters. After introducing a composed line into the casting apparatus, and appropriately actuating the mold-changing lever 49, 50, the catch 78

is raised by means of a pin 74 on the rod 72, thus releasing the lever 58. If the cam-disk 19 is in the position required for composing small characters the levers 58 and 55 return to the corresponding position, whereas the rod 60 and the levers 58 and 55 remain in the position required for the higher characters when the cam-disk 19 is in the corresponding position.

On beginning a line a change from the higher to the smaller characters may take place before the first type has been set. It is therefore necessary to prevent the catch 78 from engaging on the lug 80 when the assembling elevator 1 returns to the lower position and it must first be seen whether a change is to be made from higher to smaller characters before the composing of the line is started, or not. To this end the return of the catch 78 to its rest or inoperative position is made dependent upon a further locking device, by connecting the arm 79 of the angle-lever 78, 79 to the finger 82 by means of a connecting rod 81.

In the assembling elevator 1 there is arranged the so-called line-resistant 83^a, which is mounted on a slide 83. If the angle-lever 78 is now raised by the rod 72 the finger 82 is pushed forward so far that the slide 83 on its return to its line-beginning position after the passage of a line of matrices to the line-carriage, engages behind the finger 82. This prevents the catch 78 from engaging the lug 80 and locking the lever 58 in the appropriate position for high characters, in case the position still exists from the preceding line. As soon as the first matrix of the new line arrives in the assembling elevator the slide 83 advances so far that it releases the finger 82 and allows the catch 78 to engage the lug 80. If the cam-disk 19 is in the position demanded by the higher characters before commencing the line, and this position is changed before setting the first character, the lever 55 is also shifted to the position demanded by the small characters. But if the cam-disk 19 is changed after the first character of the following line has been set, the catch 78 first engages the lug 80 on the lever 58 and the position of the lever 55 remains uninfluenced by the change of body.

As seen from the foregoing description, the changing of the mold depends upon the relative positions of the lever 55 on the one hand and of the wheels 65 and 66 on the other hand, the position of the lever 55 corresponding to the body of type, and that of the wheels 65 and 66 to the mold in use.

Means of varying kind may be employed to obtain a change of the body of type in a matrix-setting device and my present invention may be accommodated to such means by any suitable operative connections between them and the lever 55 as to adjust the

position of said lever correspondingly to the body of the characters employed without departing from the nature of my invention.

What I claim as my invention and desire
5 to secure by Letters Patent is:

1. In matrix-setting and line-casting machines, in which a plurality of molds and matrices carrying characters of various bodies are employed, the combination, of 10 mold change controlling means controlling the change of the application of the various molds, type change controlling means controlling the change of the body of type, adjustable means operated by said mold change controlling means and adjusted thereby correspondingly to the application of said molds, further adjustable means adjusted by said type change controlling means correspondingly to the body of type in use and 15 20 adapted to engage with the former adjustable means when operated, and means for operating said latter adjustable means thereby causing a change of the application of said molds.
  - 25 2. In matrix-setting and line-casting machines in which a plurality of molds and matrices carrying characters of various bodies are employed, the combination, of an assembling elevator, mold change controlling 30 means controlling the change of the application of the various molds, type change controlling means controlling the change of the body of type, an adjustable member adapted to be adjusted correspondingly to 35 the application of said molds, a further adjustable member adapted to be adjusted by said type change controlling means correspondingly to the body of type in use and to engage said former adjustable member and 40 45 when engaging that member allowing said mold change controlling means to be operated, and operatively connecting means between said further adjustable member and said assembling elevator causing said further adjustable member to be operated by said assembling elevator when elevated.
  3. In matrix-setting and line-casting machines in which a plurality of molds and 50 matrices carrying characters of various bodies at different heights are employed, the combination of an assembling elevator, mold change controlling means controlling the change of the application of the various molds, type change controlling means controlling the change of lower and higher bodies of type, an adjustable member adapted 55 to be adjusted correspondingly to the application of said molds, a further adjustable member adapted to be adjusted by said type 60 change controlling means correspondingly to the body of type in use and to engage said former adjustable member and when engaging that member allowing said mold change controlling means to be operated, operatively connecting means between said fur- 65

ther adjustable member and said assembling elevator causing said further adjustable member to be operated by said assembling elevator when the latter is elevated, locking means locking said further adjustable member in the position corresponding to the higher body, and releasing means for releasing said locking means and adapted to be operated by said operatively connecting means between said further adjustable member and said assembling elevator when the latter is elevated. 70 75

4. In matrix-setting and line-casting machines in which a plurality of molds and matrices carrying characters of various bodies at different heights are employed, the combination of an assembling elevator, mold change controlling means controlling the change of the application of the various molds, type change controlling means controlling the change of lower and higher bodies of type, an adjustable member adapted to be adjusted correspondingly to the position of said molds, a further adjustable member adapted to be adjusted by said type change controlling means correspondingly to the body of type in use and to engage said former adjustable member and when engaging that member allowing said mold change controlling means to be operated, operatively connecting means between said further adjustable member and said assembling elevator causing that further adjustable member to be operated by said assembling elevator when elevated, locking means locking said further adjustable member in the position corresponding to the higher body, releasing means for releasing said locking means and adapted to be operated by said operatively connecting means between said further adjustable member and said assembling elevator when the latter is elevated, and means for holding said locking means in their releasing position until the first matrix of a line enters said assembling elevator. 110

5. In matrix-setting and line-casting machines in which a plurality of molds and matrices carrying characters of various bodies of different heights are employed, the combination of an assembling elevator, mold change controlling means controlling the change of the application of the various molds, type change controlling means controlling the change of lower and higher bodies of type, an adjustable member adapted to be adjusted correspondingly to the application of said molds, a further adjustable member adapted to be adjusted by said type change controlling means correspondingly to the body of type in use and to engage said former adjustable member and when engaging that member allowing said mold change controlling means to be operated, operatively connecting means between said further adjustable member and said assembling 115 120 125 130

elevator causing said further adjustable member to be operated by said assembling elevator when the latter is elevated, locking means locking that further adjustable member in the position corresponding to the higher body, releasing means for releasing said locking means and adapted to be operated by said operatively connecting means between said further adjustable member and said assembling elevator when the latter is elevated, a slide, carrying a line-resistance

and means for locking said locking means in their releasing position by means of said slide when the latter is in its line-beginning position.
